GATE LATCH

Louis A. Wagner, Corsica, S. Dak.

Application June 12, 1953, Serial No. 361,280.

4 Claims. (Cl. 292—28)

This invention relates in general to improvements in gates, and more specifically to an improved gate construction which includes means for tensioning a flexible gate.

On many farms simple gates are formed by end frame members having therebetween either woven or barbed wire. One of the end frame members is hingedly connected to a gate post while the other is adapted to be securely latched to a latch post. While such a gate construction is relatively cheap and easily built, it is difficult to properly mount so as to prevent livestock, especially hogs, from crawling under the gate.

It is, therefore, the primary object of this invention to provide an improved gate construction which includes latch means when properly actuated will cause the tensioning of the gate to properly support the same.

Another object of this invention is to provide an improved gate construction which includes a flexible gate hingedly connected to a gate post at one end and having latch means at the other end thereof carried by a latch post, the latch post means being adjustable to pull the associated end of the gate away from the gate post so as to tension the wire portion of the gate so that the gate may be retained in its proper position.

Another object of this invention is to provide an improved gate latch for flexible gates which is of an extremely simple construction and which is formed of readily obtainable materials so as to be economically feasible.

A further object of this invention is to provide an improved gate latch for flexible gates which includes a support having carried thereby a flexible member having fastening means at opposite ends thereof selectively engageable with adjacent end of a flexible gate, the support being provided with a reel for reeling in the ends of the flexible member to tension the gate.

These together with other objects and advantages which will become subsequently apparent reside in the details of construction and operation as more fully hereinafter described and claimed reference being had to the accompanying drawings forming a part hereof, wherein like numerals refer to like parts throughout, and in which:

Figure 1 is an elevational view of the gate construction which is the subject of this invention and shows the flexible gates retained in a closed position by the latch construction, an intermediate portion of the gate being omitted;

Figure 2 is an enlarged fragmentary sectional view taken substantially from the plane indicated by the section line 2—2 of Figure 1 and shows the general construction of the latch construction, an inoperative position of a handle for the reel being shown in dotted lines;

Fig. 3 is a sectional view taken substantially from the plane indicated by the section line 3—3 of Figure 2 and shows the manner in which the flexible member is carried by a support of the latch construction;

Figure 4 is a fragmentary sectional view taken substantially from the plane indicated by the section line

2

4—4 of Figure 2 and shows the arrangement of lock means for the reel;

Figure 5 is a fragmentary sectional view taken substantially from the plane indicated by the section line 5—5 of Figure 2 and shows the general cross-section and lower portion of a support and the relationship of a guide pulley carried thereon; and,

Figure 6 is a fragmentary sectional view similar to Figure 5 and shows the construction of a modified mounting for the support to facilitate hinging thereof.

Referring now to the drawings in detail, it will be seen that there is illustrated in Figure 1 a gate construction which is referred to in general by the reference numeral 10. The gate construction 10 includes a gate post 12 which is disposed in spaced relation with respect to a latch post 14. Disposed between the gate post 12 and the latch post 14 and closing the space therebetween is a gate which is referred to in general by the reference numeral 16. The gate 16 includes a first end frame member 18 which is in spaced relation with respect to a second end frame member 20. Extending between and secured to the lower and intermediate portions of the frame members 18 and 20 are strands of woven wire 22. The upper portions of the end frame members 18 and 20 are connected together by strands of barbed wire 24. It will be understood that the woven wire 22 may be replaced by additional strands of barbed wire 24 if so desired.

Hingedly connecting the gate 16 to the gate post 12 is a pair of vertically spaced hinges 26 which connect the end of frame member 18 to the gate post 12 for hinged movement. The latch post 14 is provided with a latch construction which is referred to in general by reference numeral 28 which cooperates with the end of frame member 20 to retain the gate 16 in a taut state between the gate post 12 and the latch post 14.

Referring now to Figures 2 through 5, inclusive, it will be seen that the latch construction 28 includes an elongated vertically extending support which is referred to in general by the reference numeral 30. The support 30 is formed primarily of a pair of elongated members 32 which have their ends in spaced parallel relation and their central portions in relatively greater spaced parallel relation. The extreme ends of the members 32 are connected to the latch post 14 by U-shaped mounting brackets 34 which are connected to the members 32 by transversely extending fasteners 36. As is best illustrated in Figure 3, the U-shaped mounting brackets 34 are connected to the latch post 14 by suitable fasteners 38.

The ends of the members 32 are maintained in spaced relation by guide pulleys 40 disposed between. The guide pulleys are rotatably mounted on fasteners 36. The intermediate portions of the members 32 are maintained in spaced relation by sloping transverse members 42.

Disposed at the mid-points of the members 32 and extending transversely thereof is a shaft 44. The shaft 44 is mounted for rotation and has mounted thereon intermediate the members 32 a reel 46. Wound about the reel 46 is a mid-portion of an elongated flexible member 48. It will be noted that the shaft 44 is provided with a bore 50 through the central portion thereof which is in alignment with a bore 52 through the reel 46 and that the mid-portion of the flexible member 48 extends through the aligned bores 50 and 52.

The flexible member 48 extends above and below the reel 46 and passes over the guide pulleys 40 at the upper and lower ends of the support 30. It will also be noted that the flexible member 48 passes over the transverse members 42 and is guided thereby.

Referring now to Figure 1 in particular, it will be seen that the end member 20 of gate 16 is provided with outwardly extending eyes 54 which are disposed in vertically spaced relation. The eyes 54 are generally in alignment

with the lower ends of the guide pulleys 40 and have engaged therewith hooks 56 carried by free ends of the flexible member 48.

Carried by the shaft 44 is a suitable handle 54 to facilitate rotation of the shaft 44 and the associated reel 46. When it is desired to fasten the gate 16 in a tensioned state, the hooks 56 are associated with the eyes 54 and the reel 46 rotated to short the affected length of the flexible member 48. This results in the pulling of the end of member 20 towards to latch post 14 with the resultant tensioning of both flexible member 48 and the wire portion of the gate 16 to properly position the gate 16.

In order that both the flexible member 48 and the gate 16 may be retained in their tensioned states, the reel 46 is provided with a latch which is best illustrated in Figure 4. Carried by the inner side of one of the members 32 adjacent the reel 46 is a pin 56 which has mounted thereon in eccentric relation a cam disc 58. The cam disc 58 is adapted to clamp and engage the reel 46 and is provided with a handle 60 to facilitate setting of the same.

When it is desired to open the gate 16, the lock for the reel 46 is released and the handle 54 turned in an opposite direction from that required to tension the flexible member 48 so as to permit the slackening of the flexible member 48. After the flexible member 48 has been slackened, the hooks 56 are removed from the associated eyes 54 and the gate 16 is then free to be moved to an open position.

Referring now to Figure 2 in particular, it will be seen that carried by one of the members 32 on the outer surface thereof is a supporting bracket 62. The supporting bracket 62 is intended to receive the handle 54 when not in use so as to prevent the accidental rotation of the reel 46 by an animal.

Referring now to Figure 6 in particular, it will be seen that there is illustrated a modified mounting structure for the support 30. The latch post is in the form of a metallic latch post, such as the latch post 64, there may be provided additional mounting brackets 66 which are U-shaped. The mounting brackets 66 may be provided with clamping bolts 68 to facilitate their clamping to the metallic latch post 64. The mounting bracket 66 is connected to the mounting bracket 34 the support 30 by a hinge connection 70 which facilitates the pivoting of the support 30 with respect to mounting brackets 66.

In view of the foregoing, we see that there has been illustrated and described a simple gate construction which facilitates the proper positioning of a flexible gate. Not only is the gate construction of such a nature whereby the gate thereof is retained in a tensioned state when in a closed position, but the latch construction is such that the gate may be quickly and easily opened and closed.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A latch assembly for gates, said latch assembly comprising an elongated support including a pair of elongated support members having closely spaced end portions and widely spaced central portions, a transverse shaft extending through and journaled in said central portion, a crank on said shaft externally of said support, a reel carried by said shaft intermediate said central portions, guide members mounted between said end portions at opposite ends of said support, a flexible latch member having a central portion entrained over said reel and intermediate portions entrained over said guide members.

2. A latch assembly for gates, said latch assembly comprising an elongated support including a pair of elongated support members having closely spaced end portions and widely spaced central portions, a transverse shaft extending through and journaled in said central portion, a crank on said shaft, externally of said support, a reel carried by said shaft intermediate said central portions, guide members mounted between said end portions at opposite ends of said support, a flexible latch member having a central portion entrained over said reel and intermediate portions entrained over said guide members, intermediate guide members for said flexible members extending between and connecting together said central portions.

3. A latch assembly for gates, said latch assembly comprising an elongated support including a pair of elongated support members having closely spaced end portions and widely spaced central portions, a transverse shaft extending through and journaled in said central portion, a crank on said shaft externally of said support, a reel carried by said shaft intermediate said central portions, guide members mounted between said end portions at opposite ends of said support, a flexible latch member having a central portion entrained over said reel and intermediate portions entrained over said guide members, said flexible member having a central part passing through said reel and said shaft to anchor said flexible member.

4. A latch assembly for gates, said latch assembly comprising an elongated support including a pair of elongated support members having closely spaced end portions and widely spaced central portions, a transverse shaft extending through and journaled in said central portion, a crank on said shaft externally of said support, a reel carried by said shaft intermediate said central portions, guide members mounted between said end portions at opposite ends of said support, a flexible latch member having a central portion entrained over said reel and intermediate portions entrained over said guide members, and cam lock means on one of said central portions selectively engaged with said reel to lock the same against rotation.
